Patented Mar. 31, 1970

217,066

POCKET LIGHTER OR SIMILAR ARTICLE

Dieter Rams, Konigstein im Taunus, Germany, assignor to Braun Aktiengesellschaft, Frankfurt am Main, Germany, a corporation of Germany

Filed Dec. 19, 1968, Ser. No. 15,051

Claims priority, application Germany July 4, 1968

Term of patent 14 years

Int. Cl. D27—05

U.S. Cl. D48—27

FIG. 1 is a perspective view of a pocket lighter, or similar article, showing my new design;

FIG. 2 is a side elevational view thereof, the opposite side being substantially the same in appearance;

FIGS. 3 and 4 are left and right end elevational views thereof, respectively; and

FIG. 5 is a top plan view thereof.

The bottom of the pocket lighter or similar article is plain.

I claim:

The ornamental design for a pocket lighter or similar article, substantially as shown and described.
